UNITED STATES PATENT OFFICE

CARL J. CHRISTOPHER, DECEASED, LATE OF CHICAGO, ILLINOIS, BY STATE BANK OF CHICAGO, EXECUTOR, OF CHICAGO, ILLINOIS

DENTAL BITE PLATE

Application filed January 9, 1930. Serial No. 419,489.

This invention relates to dental appliances and more particularly to a device known in the art as a bite plate and employed in connection with the making and fitting of artificial dentures, and by the use of which it is aimed to secure accuracy in articulation.

In practice it has been found that greater accuracy is attained when the tongue of the patient is elevated and held against an abutment, and to this end the principal object of the invention is to produce a dental bite plate having provision for applying to its upper and lower surfaces, respectively, the wax or material in which the impression is to be made, said device having a transverse abutment portion over which the tongue of the patient is hooked and firmly supported during the process of taking the impression. The invention further consists in the general arrangement and novel structural features of the device as hereinafter described and pointed out with particularity in the appended claims.

In the accompanying drawings illustrating a practical adaptation and application of the invention:

Fig. 1 is a schematic sectional view illustrating the use of the device in taking the impression;

Fig. 2 is a plan view of one form of the device;

Fig. 3 is a transverse section on the line 3—3 of Fig. 2;

Fig. 4 is a top plan view of a modified form of the device;

Fig. 5 is a longitudinal section on the line 5—5 of Fig. 4; and

Fig. 6 is a transverse section on the line 6—6 of Fig. 4.

Referring now to the drawings, the numeral 10 designates generally the bite plate, this plate preferably being made of a sanitary non-corrosive metal possessing sufficient self-supporting rigidity, yet being somewhat pliable so as to be readily bent, by hand and at the will of the operator, and thereby changed in contour in order to more conveniently adapt the device to each individual case. Obviously, the device may be stamped

from sheet metal or it may be produced by die casting or by any other approved or desirable method of production.

As shown, the device of the present invention is provided with a central opening 11, thereby producing the side portions 12 which are connected by the intermediate front portion 13, whereby that part of the device to which the wax or impression taking substance is applied is substantially U-shaped. The intermediate portion 13 has a forwardly extending tongue 14 constituting a handle for facilitating the manipulation of the device in placing it in and removing it from the mouth of the patient, while the end portions of the side members 12 are connected by a cross bar or bridge portion 15. Preferably, this cross bar or bridge portion 15 is curved forwardly, as shown more clearly in Figs. 2 and 4 of the drawings, and it is arched as shown in Figs. 3, 5 and 6 of the drawings. In Fig. 3 it is noted that the arching of the cross bar or bridge portion 15 is only slightly above the plane of the side portions 12, whereas, in Fig. 6, said portion 15 is arched to a comparatively higher extent, and this is to illustrate an important feature of the present invention, in that the preferred characteristic metal of which the device is composed permits of the ready bending of the cross bar or bridge portion 15 by the operator in order to adapt the device to universal use in the mouths of patients where there is a considerable variation in the height of the vaulted roofs thereof, the object being, in the use of the device, to utilize the cross bar or bridge portion 15 as an abutment for the tongue of the patient and to support the tongue well towards the roof of the mouth.

In some cases the bite plate side and end portions 12 and 13, respectively, may be made concavo-convex in cross section as shown more clearly in Fig. 3 of the drawings, this formation being to afford laterally retentive resistance for the wax or impression material when applied to the surfaces of said portions of the device; and, to avoid discomfort to the patient, the cross bar or bridge 15 is preferably rounded in cross section as shown more clearly in Fig. 5 of the drawings, this round-

ing of the member 15 being produced by embossing it upwardly, by which provision no relatively sharp edges are presented to the discomfort of the patient. Instead of making the side and end portions 12 and 13 concavo-convex in cross section, said portions may be made flat throughout the extent thereof, and be provided with a series of apertures 16, said apertures being primarily provided for the purpose of securing better adhesion of the wax or impression material to the surface of the device; that is to say when the wax or other impression material is pressed upon the plate, a portion thereof enters said perforations 16, whereby a more secure bond is afforded, particularly when the wax or other impression material is applied to both sides of the plate.

In using the bite plate, according to an approved method, a roll of wax is first placed upon the upper surface of the plate and the plate is then placed in the mouth of the patient and the wax pressed against the upper ridge. The upper impression having thus been made, the device is removed from the mouth of the patient and a roll of wax or other suitable material is placed on the lower surface of the bite tray. The bite tray is again placed in the mouth and the upper impression, previously made, is reseated on the upper ridge. The patient, with his tongue hooked over the cross bar or bridge portion 15 and thereby firmly supported, is then instructed to close the lower mandible and the lower ridge impression is thereby produced in the impression material on the under side of the bite plate, and the upper and lower impressions are thus produced in perfect register occlusion.

The device of the present invention, as hereinbefore stated, is primarily intended for use as a bite plate or tray, but it has the further advantages of being utilized in other operations in the making of artificial dentures and it is therefore not specifically limited to such first mentioned usage. So, too, the device may be modified considerably in its construction and arrangement without departing from the spirit and scope of the invention as defined by the appended claims. The invention, therefore, is not limited to the specific details of structure shown in the accompanying drawings.

Having thus described the invention, what is claimed as new and desired to secure by Letters Patent is:

1. A dental bite plate having a central opening and a transverse bridge member connecting the side portions of said plate at the rear thereof and affording an abutment and tongue rest.
2. A dental bite plate having a central opening, defining continuous side and front impression supporting portions, and a transverse bridge portion connecting said side por-

tions, whereby to afford an abutment and tongue support.

3. The herein described dental appliance comprising a centrally apertured plate providing side and front impression supporting portions, the front portion having a forward handle extension, and a transverse bridge portion connecting said side portions and affording an abutment and tongue support.

4. The herein described dental appliance comprising a plate of pliable yet self-supporting metal, said plate having a central opening whereby to define characteristic continuous side and front portions, said front portion having a forward handle extension, and an arched cross member connecting said side portions whereby to afford an abutment and tongue support.

In testimony whereof, petitioner, by a duly authorized officer, has signed this specification.
